By his Attorney

UNITED STATES PATENT OFFICE.

BENJAMIN E. GETCHELL, OF PLAINVILLE, CONNECTICUT, ASSIGNOR TO THE TRUM-BULL ELECTRIC MFG. COMPANY, OF PLAINVILLE, CONNECTICUT, A CORPORATION OF CONNECTICUT.

INCLOSED SWITCH.

Application filed June 24, 1921. Serial No. 479,992.

My invention relates particularly to interlocking mechanism for so-called safety switches.

It is customary in such constructions to provide means for preventing the box or receptacle from being opened when the switch is in the closed circuit position.

The main object of the present invention is to provide means for permitting the opening of the box without opening the switch. To accomplish this purpose I so construct the parts that the interlock between the cover and the box may be rendered temporarily 10 inoperative by means of a key.

Fig. 1 is a front view of a safety switch embodying the improvements of my invention with the switch handle in the open circuit position.

Fig. 2 is a side view showing the switch handle in the closed circuit position.

Fig. 3 is an enlarged detail of part of the interlocking device showing the interlocking bolt in dot and dash lines in the disengaged position.

Fig. 4 is a front view of the interlocking parts which are attached to or carried by the body of the box.

Fig. 5 is a sectional view of the interlocking parts.

Fig. 6 is an interior view of the interlocking parts in the open circuit position of the switch and with the cover slightly open.

Fig. 7 is a similar view in the closed circuit position and with the cover closed.

Fig. 8 is a perspective view of part of the latch mechanism.

The body 10 and the cover 11 of the box may house any suitable kind of switch mechanism. The cover will be usually hinged 40 along one edge, in this case along the left hand edge as viewed in Fig. 1. The operating handle 12 is pivoted in one side of the box and may have a hub 13 connected directly or indirectly to it, the hub in turn carrying a crank or arm 14 for operating the switch mechanism proper (not shown). The box may be provided with a snap catch 15 adapted to operate through an opening 16 in the cover. The handle and box may 50 also be provided with members such as 17 and 18 which may be conveniently connected together either by padlock or a sealing wire (not shown).

On the inside of the box a notched disc

19 is secured to the hub of the handle and 55 adapted to be engaged by a pivoted latch 20 when the switch is in the open circuit position and the cover is open as shown in Fig. 6. This latch 20 is held yieldingly against the member 19 by means of a spring 21. A 60 pin or projection 22 carried by the cover is adapted to enter the notch 23 in the side of the box and engage the inclined shoulder 24 of the latch 20 as the cover is being closed. This action retracts the latch 20 from its engagement with the handle locking notch in the disc 19, so the switch handle and switch mechanism may be operated to open or close the circuit as desired. With the switch in the closed circuit position, the disc 19 is in 70 the position of Fig. 7 with the latch 20 held by means of the disc so that the shoulder 25 stands in the path of the projection 22 and normally prevents the cover from being opened.

To permit the cover to be opened when the switch is in the closed circuit position, it will be seen that it is simply necessary to retract either the latch 20 or the projection 22. I accomplish this by mounting the 80 projection 22 so that it may be retracted. A member 26 which carries the projection 22 is provided with flanges 27 and 28, some of which are secured to the cover. The projection 22 is carried by a spring arm 29 in 85 such a position that the key 30 inserted through the key slot 31 and into the step 32 may retract the arm 29 and the locking bolt 22, as indicated by the dot and dash lines of Fig. 3. The shoulder 33 acts as a 90 stop or abutment for the blade of the key in the dotted position of Fig. 3. When the projection 22 is retracted, it is clear that the cover may be opened without opening the circuit through the switch and the cover 95 may be closed again when desired. So also, it will be noted that when the cover has been opened with the switch in the closed circuit position, there is nothing to prevent the switch being opened, although as soon as 100 it is open the latch 20 will snap into the notch and the disc 19 and lock the switch in the open circuit position.

I claim:

1. In an inclosed switch construction, a 105 casing including a body and a movable cover, a switch operating member within said casing, an operating handle outside of

said casing connected to said member, a latch within said casing adapted to hold the switch member in the open circuit position when the cover is opened, a latch retracting member carried by the inside of said cover and including a spring arm, means carried by said latch normally cooperating with said retracting member to hold the cover closed when the switch is in the closed circuit position, and a removable member adapted to engage said spring arm to operate said latch retracting member.

2. In an inclosed switch a casing including a hinged cover, a switch and an operating member for said switch mounted inside of said casing, an operating handle outside of said casing connected to said operating member, a latch within said casing for engaging said operating member to lock the switch in the open circuit position when the cover is open, a bracket carried by the inside of said cover, a movable bolt carried by said bracket for normally engaging said latch to lock the cover closed when the switch is in the closed circuit position, said cover having means for receiving a key for disengaging said bolt from said latch and releasing said cover.

3. An inclosed switch comprising a casing, a cover hinged at one edge thereof, a switch

mounted within said casing, a switch operating member within said casing, a latch co-operating with said operating member to hold the switch in the open circuit position when the cover is open, a bracket carried by the inside of said cover, a spring carried by said bracket, a bolt carried by said spring and adapted normally to contact with said latch to lock the cover closed when the switch is in the closed circuit position, said cover having a key receiving hole whereby a removable key may be inserted to engage said spring and retract said bolt from engagement with said latch.

4. An inclosed switch comprising a box including a body and a cover, a switch mounted within said box, a spring arm carried by the inside of said cover, a bolt carried by and movable with said arm, a latch mounted in said box normally co-acting with said bolt to hold the cover closed when the switch is in a closed circuit position, said cover having a keyhole opening adjacent said spring arm adapted to permit the insertion of a removable key for retracting said bolt from said latch and permitting said cover to be opened when the circuit is closed.

BENJAMIN E. GETCHELL.
